WALTER ROTHER, OF DETROIT, MICHIGAN, ASSIGNOR TO R. E. L. TOOL AND DIE COMPANY, OF DETROIT, MICHIGAN, A COPARTNERSHIP COMPRISING WALTER ROTHER, ELMER J. FOX, AND LEWIS W. LOVET.

VALVE-REFACING TOOL.

1,387,666.

Specification of Letters Patent. Patented Aug. 16, 1921.

Application filed August 4, 1920. Serial No. 401,094.

To all whom it may concern:

Be it known that I, WALTER ROTHER, a citizen of the United States, residing at Detroit, in the county of Wayne and State 5 of Michigan, have invented a new and useful Valve-Refacing Tool, of which the following is a specification.

This invention relates to valve refacing tools, and more particularly to tools for 10 facing the tappet valves of internal combustion engines.

It is the object of the invention to provide a tool, particularly adapted for the use of motor vehicle repair shops and 15 garages, which tool is adapted to quickly and accurately effect the refacing of a tappet valve.

In attaining this object the invention contemplates a cutting tool adapted to be manually rotated through a suitable crank and gearing and provided with a plurality of 20 conically inclined cutting blades forming a seat for the valve, and a clamping means adjustable to feed the valve against said 25 blades with such pressure as will effect the desired cut, said clamping means having such engagement with the valve as to restrain the same from rotation.

A preferred embodiment of the invention 30 is illustrated in the accompanying drawing, wherein,

Figure 1 is a view of the tool in side elevation.

Fig. 2 is a plan view of the same.

Fig. 3 is a vertical sectional view taken 35 on line 3—3 of Fig. 2.

Fig. 4 is a horizontal sectional view taken on line 4—4 of Fig. 1.

In these views, the reference character 1 40 designates a base plate apertured as indicated at 2 for engagement by screws or the like whereby the tool may be secured to a suitable work bench or table. From said base there rises centrally and integrally a 45 socket journal bearing 3 receiving a tubular stub shaft 4 which integrally carries a bevel gear 5 just above said bearing. Said shaft is rotatively retained in said bearing by a pin 6 radially mounted in the bearing and 50 projecting into an annular groove 7 in the shaft. Preferably the pin 6 has a pressure fit in a bore of the bearing, being threaded upon its outer end for engagement by a nut 8 which bears upon a washer 9 seated

against the bearing 3, and which when rotated in a proper direction will effect removal of the pin. The gear 5 is engaged by a driving bevel gear 10, fast upon a horizontal shaft 11, which is journaled in a bearing 12 integrally rising from the base 1, and a hand crank 13 is mounted upon said shaft outside of said bearing. The gear 5 is formed in its top face with a conical depression 14, having an incline equal to the standard incline of an engine 65 tappet valve. Within said depression, there is mounted a plurality of cutting blades 15 arranged in channels 16 in the wall of said depression and conforming to the angle of inclination of said wall. Said blades are 70 rigidly held in their respective channels by any suitable means, such as the screws 17. Preferably the blades 15 are substantially flush with the conical wall of the depression 14 but have cutting edge portions projecting sufficiently above said wall to effect 75 refacing of a valve. At 18 is indicated a tappet valve engaging the blades 15, the stem 19 of said valve being accommodated within the opening of the tubular shaft 4 80 and within an alined opening 20 in the base 1.

As a common means for holding the valve 18 against rotation and for feeding said valve against the cutting blades 15, there 85 is provided a screw 21 mounted co-axially with the shaft 4 above the same, the lower end of said screw being provided with a head 22 for bearing upon the valve 18, and the upper end having an actuating handle 23 thereupon. Intermediate said head and handle the screw 21 engages a mounting 24 terminally formed upon a horizontal arm 25 upon the upper end of a stem 26 which fits into a socket 27 integrally rising 90 from the base 1. A set-screw 28 is mounted in the socket 27 to bear upon the stem 26 and hold the latter in a desired position of both sliding and rotative adjustment.

Considering now the operation of the de- 100 scribed invention, when the same is not in use, the stem 26 is rocked to dispose the mounting 24 out of alinement with the cut- 105 ter axis, as is shown in Fig. 2. After a tappet valve requiring refacing has been dis- 105 posed within the depression 14, resting upon the blades 15, and with its stem depending through the central opening of the shaft 4

and opening 20 of the base, the stem 26 is rocked to align the screw 21 with the shaft 4. The handle 23 is then turned until the screw 21 is lowered sufficiently to engage the pins 29 with sockets 30 of the tappet valve, and thus lock said valve against rotation relative to said screw. The operator, while maintaining with one hand an adjustment of the screw 21 such as to press the valve 18 against the blades 15 turns the crank 13 with the other hand, and thus rotatively drives the blades 15. If necessary, the screw 23 may be turned sufficiently during rotation of the crank to gradually feed the tappet valve 15 against the blades, as the inclined bearing face of said valve is cut away. During the cutting operation, the set-screw 28 is kept tightened to maintain the screw 21 rigidly in alignment with the shaft 4. Sufficient clearance is afforded within the opening 20 and that of the shaft 4 around the valve stem 19 to allow escape of the fine cuttings which are removed from the valve by the blades.

The described tool satisfies the demand for a comparatively inexpensive means for quickly and accurately effecting the refacing of tappet valves.

What I claim is:—

1. A valve refacing tool comprising a shaft, driving means for said shaft, a plurality of cutting blades carried by said shaft, and conically inclined to the axis thereof, the cutting edges of said blades providing a seat for a tappet valve, and means for maintaining an axial pressure upon a tappet valve engaging said blades and for restraining said valve from rotation.

2. A valve refacing tool comprising a shaft, driving means for said shaft, a head upon said shaft formed with a conical recess having the angle of inclination of a standard tappet valve, a plurality of blades carried by said head within said recess forming to the angle of inclination thereof, the cutting edges of said blades being adapted to provide a seat for a tappet valve, and means for maintaining an axial pressure upon a tappet valve engaging said blades and for restraining said valve from rotation.

3. A valve refacing tool comprising a shaft, driving means for said shaft, a plu-

rality of cutting blades carried by said shaft, and conically inclined to the axis thereof, the cutting edges of said blades providing a seat for a tappet valve, a screw aligned with said shaft, a clamping head upon one end of said screw for pressing a valve against said blades, an actuating handle upon the other end of said screw, and a mounting for the screw adjustable to shift the screw into or out of alignment with said shaft.

4. A valve refacing tool comprising a shaft, driving means for said shaft, a plurality of cutting blades carried by said shaft, and conically inclined to the axis thereof, the cutting edges of said blades providing a seat for a tappet valve, a screw parallel to said shaft, a rock-arm providing a mounting for said screw adjustable to shift the screw into or out of alignment with said shaft, means for holding said arm rigid when the screw is aligned with said shaft, a head upon one end of the screw engageable with a tappet valve seated on said blades to press the valve against the blades and adapted to restrain the valve from rotation, and an actuating handle carried by said screw.

5. A valve refacing tool comprising a base, a socket bearing integrally rising from said base, a tubular shaft journaled in said bearing, a gear integrally surmounting said shaft and formed with a conical depression, the incline of said depression being equal to that of a standard tappet valve, said tubular shaft communicating at one end with said depression and at the other with an opening through said base, a plurality of cutting blades secured to said gear within said depression and conforming to the incline of the latter, said blades providing a seat for a tappet valve, the stem of which is accommodated by the opening of said tubular shaft and base, an adjusting screw for exerting pressure upon said tappet valve against said blades, a mounting for said screw adjustable to shift the screw into or out of alignment with said shaft, a second gear having driving engagement with the first mentioned gear and a crank for driving said gears.

In testimony whereof I sign this specification.

WALTER ROTHER.
